UNITED STATES PATENT OFFICE.

WILLIAM S. BRADSHAW, OF SAN JOSE, CALIFORNIA.

BALING-PRESS.

SPECIFICATION forming part of Letters Patent No. 786,948, dated April 11, 1905.

Application filed April 18, 1904. Serial No. 203,655.

To all whom it may concern:

Be it known that I, WILLIAM S. BRADSHAW, a citizen of the United States, residing at San Jose, in the county of Santa Clara and State 5 of California, have invented new and useful Improvements in Baling-Presses, of which the following is a specification.

My invention relates to improvements in baling-presses or hay-presses of the vertical 10 type, and pertains particularly to means for automatically operating the door of the press-box. Its object is to provide a novel, simple, safe, positive, and practical means for opening and closing the door.

It consists of the parts and combination of 15 parts, as hereinafter more fully described and claimed, having reference to the accompanying drawings, in which—

Figure 1 is a side elevation showing door 20 closed. Fig. 2 is a part plan view of same. Fig. 3 is a side elevation opposite to Fig. 1, showing door open. Fig. 4 is a plan view, partly in section, through chain-pulley and shaft-bearing.

The parts of the machine that are essentially 25 old are shown in dotted lines.

A represents a press-box of well-known construction; 2, a follower movable therein by any suitable means not necessary here to 30 show; 3, the door or shutter hinged at the lower edge and movable between the usual guides 4, and 5 the sweep of the ordinary horse-power.

Secured to the sides of the press and the 35 guides 4 are brackets or supports 6 for the journals of the rock-shaft 7.

8 represents toggles, each with one member fixed to shaft 7 and with the other suitably pivoted to the door near its top edge. By 40 an oscillation of shaft 7 in one direction the toggles act to close the door. An oscillation in the opposite direction opens the door. The means by which these successive operations are performed constitute the essential features 45 of my invention.

One end of shaft 7 carries a drum or grooved pulley 9 and the other a similar drum or pulley 10. For purposes of economy in construction and ease of assembling the parts I pre-

fer to make shaft 7 polygonal in cross-section 50 and to cast each drum with an integral hub portion 11, adapted to fit over the shaft and provided with suitable locking means or keys, whereby the drums may be fixed rigidly on the shafts and all made to turn in unison. The 55 hub parts 11 serve as bearings and save the necessity of turning down the shaft or providing separate bearing-sleeves. A chain or like flexible connection 12 is fixed to drum 9 and passes over the top thereof. The other 60 end of the chain connects to a radius-rod 13, pivoted to the press-box. This same chain or a continuation 14 thereof leads from the rod 13 back around a pulley 15 and connects with a lever 16, disposed in the path of a projection 17 on sweep 5. This lever is preferably formed with a bifurcated bracket portion 18, which enables it to be substantially supported 65 on the horse-power frame. In the rotation of the sweep the lever is engaged to exert a 70 tension on the chain and rotate pulley 9 to close the door.

Heretofore more or less danger has attended the closing of press-doors by reason of their too sudden action, and often the men occupied in feeding the press-box where not given timely warning were caught in the door and severely injured. I place my operating-lever 16 back of the point of farthest outward travel of the sweep on that side of the machine, so that the period of contact of the stop on the sweep and the lever will be considerably prolonged and the closing of the door will be rendered more gradual. 75

The radius-rod 13 acts in lieu of a direction-pulley, is simple, occupies little room, and allows for a slackening up to some extent of the downward pull on pulley 9 as the door closes. 80

As the door is closed the toggles are thrown a bit beyond center to carry their members 90 slightly out of line and are supported against the stops or knee-brackets 19 to hold the door tight shut while the follower is reciprocated to compress the charge. The opening of the door is effected by means of a chain 95 or like flexible connection 20, fastened at one end to drum or pulley 10 and passed around beneath the latter and attached to the fol-

lower. The chain 20 is ordinarily slack enough to allow the door freely to open and close at all times, except when the follower is lifted above the door-opening. When the 5 door closes, the chain 20 will be drawn taut just as the follower passes the top edge of the door. The further uplift of the follower to complete the compression of the charge acts to rotate the drum 10 and open the door, the 10 diameter of the drum being sufficient to unwrap enough chain to allow the follower to move to its full limit upward. Thus a movement of the sweep acting through pulley 9 closes the door, and the upward movement of 15 the follower acting directly through pulley 10 opens it.

I may interpose a stiff coil-spring 21 in the connections between pulleys 9 and 15, which will be sufficiently strong to close the door 20 under ordinary circumstances; but should the horses start when the hay was only half-way in or should a fork-handle be caught in the door, either of which happenings would break the door, the spring would give enough to render the door non-breakable and less dangerous. The next revolution of the sweep would 25 close the door.

Having thus described my invention, what I claim, and desire to secure by Letters Patent, is—

1. In a baling-press, the combination of the press-box, a follower therein, a door for said press-box, door-closing means including a rock-shaft and toggles, and a connection from 35 one side of the shaft for rocking the shaft in one direction, and door-opening means including the aforesaid shaft and toggles, and a flexible connection from the opposite side of the shaft to the follower for rocking the shaft 40 in an opposite direction.

2. In a baling-press, the combination of a press-box, a follower therein, a door for the press-box, brackets extending from the press-box, a transverse shaft journaled in said 45 brackets, toggles between the shaft and the door, pulleys on opposite portions of the shaft, a flexible connection attached to one of said pulleys and passing over the same for rocking the shaft in one direction, a flexible connection 50 attached to the other pulley and passing under the same, for rocking the shaft in an opposite direction, and means for actuating the connection.

3. In a baling-press, the combination of a 55 press-box, a follower therein, a door for said press-box, door-closing means, and means for opening the door, said opening means including a rock-shaft, toggles having one member fixed to said shaft and the other pivoted to 60 the door, a fast pulley on the shaft and direct flexible connections between the pulley and

follower, and knee-brackets 19 on the door to limit the inward movement of said toggles.

4. In a baling-press, the combination of a 65 press-box, a follower therein, a door for said box, a sweep, devices in the path of the sweep and operable thereby, a rock-shaft, toggles having one member fixed to the shaft and the other pivoted to the door, fast pulleys on said shaft, door-closing means including flexible 70 connections between one of said pulleys and the said devices operable by the sweep, said door-opening means including flexible direct connections between the other of said pulleys and the follower.

5. In a baling-press, the combination of a 75 press-box, a follower therein, a door for said box, a sweep, devices operable thereby, a rock-shaft, toggles having one member fixed to the shaft and the other pivoted to the door, fast 80 pulleys on said shaft, door-closing means including flexible connections between one of said pulleys and the devices operable by the sweep, door-opening means including flexible direct connections between the other of said 85 pulleys and the follower, said pulleys having integral sleeve portions fitting said shaft and serving as journals therefor substantially as described.

6. In a baling-press, the combination of a 90 press-box, a follower therein, a door for said box, a sweep, a rock-shaft, toggles having one member fixed to the shaft and the other pivoted to the door, door-closing means, door-opening 95 means, said door-closing and door-opening means each including a pulley fast on said shaft, a pulley disposed adjacent to the sweep, a lever operatable by said sweep, flexible connections between the lever and said fast pulley, and an expansion-spring interposed in 100 said connections.

7. In a baling-press, the combination of a 105 press-box, a follower therein, a door for said box, a sweep, a rock-shaft, toggles having one member fixed to the shaft and the other pivoted to the door, fast pulleys on said shaft, door-closing means including flexible connections between one of said pulleys and devices 110 operable by the sweep, door-opening means including flexible direct connections between the other of said pulleys and the follower, and an expansion-spring interposed in said door-closing flexible connections for the purpose specified.

In testimony whereof I have hereunto set 115 my hand in presence of two subscribing witnesses.

WILLIAM S. BRADSHAW.
